UNITED STATES PATENT OFFICE.

WILLIS J. BOYLE, SR., OF LOS ANGELES, CALIFORNIA.

DESIGN FOR A CANTEEN.

50,182.

Specification for Design.

Patented Jan. 16, 1917.

Application filed July 15, 1916. Serial No. 109,577. Term of patent 14 years.

To all whom it may concern:

Be it known that I, WILLIS J. BOYLE, Sr., a citizen of the United States, residing at Los Angeles, in the county of Los Angeles and State of California, have invented a new, original, and ornamental Design for Canteens, of which the following is a specification, reference being had to the accompanying drawing, forming part hereof.

In the drawing, Figure 1 is a perspective

view, and Fig. 2 is an edge view, of a canteen, each one showing my new design.

I claim:

The ornamental design for a canteen, as shown.

WILLIS J. BOYLE, Sr.
